Primary Examiner — Philip S Hyder*Assistant Examiner* — Darlington Ly*(74) Attorney, Agent, or Firm* — Cantor Colburn LLP(57) **CLAIM**

We claim, the ornamental design for an element of a vehicle bumper system, as shown and described.

DESCRIPTION

FIG. 1 is a front perspective view of an element of a vehicle bumper system, showing an embodiment of our new design; FIG. 2 is a rear perspective view of the embodiment shown in FIG. 1;

FIG. 3 is a top plan view of the embodiment shown in FIG. 1; FIG. 4 is a bottom plan view of the embodiment shown in FIG. 1;

FIG. 5 is a front elevation view of the embodiment shown in FIG. 1;

FIG. 6 is a rear elevation view of the embodiment shown in FIG. 1;

FIG. 7 is a right elevation view of the embodiment shown in FIG. 1; and,

FIG. 8 is a left elevation view of the embodiment shown in FIG. 1.

The broken lines illustrate portions of element of a vehicle bumper system that forms no part of the claimed design.
